UNITED STATES PATENT OFFICE.

GEORGE W. MCGILL, OF NEW YORK, N. Y.

SHIPPING-TAG.

SPECIFICATION forming part of Letters Patent No. 663,355, dated December 4, 1900.

Application filed August 31, 1899. Serial No. 729,071. (No model.)

To all whom it may concern:
Be it known that I, GEORGE W. MCGILL, a citizen of the United States, residing at New York, in the county of New York and State of New York, have invented new and useful Improvements in Shipping-Tags, of which the following is a specification.

This invention relates to that class or type of shipping-tags wherein a doubled tying-string is connected with an address-card of comparatively thick or tough paper and the two free ends of the string are knotted at or near their point of attachment to enable the addressed card to be tied to the tying-string or otherwise connected with a bundle or package designed to be expressed or shipped. The common or well-known shipping-tag has the string passed through an eyelet near one end and is knotted, so that the two free ends can be tied to a package. Such construction is objectionable in that the card or tag is not reinforced and is more or less readily torn away at or in advance of the eyelet and is lost. Various methods have been proposed to reinforce or strengthen the address-card and secure an efficient attachment of the doubled or two-end tying-string thereto; but all are more or less objectionable in that they do not successfully accomplish the desired result, and the cost of manufacturing the tags with their doubled or two-end string is considerably increased, which has resulted in their not coming into extensive or general use, although much desired from the point of view of strength, durability, and safety in expressing or shipping packages where the sole address is on the tag tied to the tying-string or otherwise secured thereto.

The objects of my invention are to avoid the objections hereinbefore referred to; to secure all the required reinforcing and strengthening of the card; to obtain a permanent, durable, effective, and strong connection of the doubled or two-end string with the card without appreciably increasing the cost of manufacture; to enable the card, if desired, to be made of a single thickness of material, such as paper, and to so arrange the string that while reinforcing and strengthening the card it extends from the center of one end thereof as two strands for conveniently connecting the tag to the package.

To accomplish all the objects, my invention consists in a shipping-tag possessing the characteristic features of construction hereinabove described and claimed, reference being made to the accompanying drawings, in which—

Figure 1 is a plan view of my new and improved shipping-tag. Fig. 2 is a sectional view taken on the line 2 2, Fig. 1. Fig. 3 is a plan view showing a modified arrangement of the strengthening tying-string; and Fig. 4 is a sectional view taken on the line 4 4, Fig. 3.

In order to enable my invention to be clearly understood, I will now describe the same in detail, referring to the drawings, wherein the numeral 5 indicates a shipping-tag, preferably composed of a single layer of comparatively thick and tough paper of any desirable configuration or outline. As shown in Fig. 1, the tag is a substantially rectangular card having the two corners at one end cut away, as at 6. The median line of the card is constructed with a plurality of string-holes, as at 7, 8, and 9, the end holes preferably containing metallic eyelets. The tying-string is doubled to form two strands 10 and 12, which are laced back and forth through the string-holes and knotted together in or at the eyeleted string-hole 7 near one end of the card, from whence the two ends 13 and 14 of the doubled string extend any required length to enable them to be tied to a package, which is ordinarily effected by properly securing them to the cord used to tie up the package. The two strands 10 and 12 are laced through the string-holes, as stated, and therefore a part of each strand extends along a part of one surface of the card and thence along a part of the opposite surface, as clearly shown in Fig. 2. The doubled string is drawn comparatively taut before being knotted together in the eyeleted string-hole 7, and consequently the string reinforces and strengthens the card centrally throughout its entire length and prevents the card being torn from its attaching-string, particularly at or near the eyeleted string-hole in which the doubled string is knotted. In Figs. 3 and 4 the card composing the tag 15 is provided with convex or rounded corners 16 and near each end with a transverse row of string-holes 17, 18, and

19, while centrally between the ends, near each side edge, is a string-hole 20. The doubled string 21 is laced back and forth through these string-holes, and portions of the string 5 lie against opposite sides of the card and run transversely and longitudinally thereof, thus reinforcing and strengthening the card around all its marginal portions. The two strands are brought together and knotted at 10 or near the center string-hole 18 at one end of the card, and preferably the two tying ends 22 and 23 of the string are knotted, as at 24, or otherwise fastened together contiguous to the end of the card. The two ends of the 15 string serve to attach the tag to the package—as, for instance, by tying them to the cord used in tying the package-wrapper.

Inasmuch as the string is doubled and bears at its bend or bends against the edge of the 20 string hole or holes in the end opposite the end where the card is tied to the package, any longitudinal pull on the card is distributed throughout its length and not at a single point at one end, in consequence of which the 25 string cannot under ordinary conditions or circumstances be pulled out of the card or the latter torn from the string.

The interlacing of a tying-string with a shipping-tag is particularly advantageous and 30 useful in obtaining an effective, simple, and comparatively inexpensive reinforcing and strengthening of the tag and avoiding the liability of tearing the same from the string at the end which is tied to the package.

35 Having thus described my invention, what I claim is—

1. As an improved article of manufacture, a shipping-tag having string-holes in its opposite end portions and intermediate the same, 40 and a tying-string interlaced through said

string-holes and secured to permanently fix it to the tag, substantially as described.

2. A shipping-tag having string-holes and a tying-string laced back and forth through said string-holes and lying against the opposite surfaces of the tag from one end portion to the opposite end portion to reinforce and strengthen the tag practically its full length, and secured to permanently fix it relatively to the tag, substantially as described. 15 50

3. A shipping-tag having a tying-string interlaced therewith at each end portion and between the end interlacings, extending along opposite sides of the tag substantially its entire length and knotted at one end portion to 55 permanently attach and fix it relatively to the tag, substantially as described.

4. A shipping-tag having string-holes in its opposite end portions and intermediate thereof, and a doubled tying-string laced back and 60 forth through said holes longitudinally of the tag and its two tying end portions knotted together at one end portion of the tag, substantially as described.

5. A shipping-tag having string-holes in its 65 opposite end portions and intermediate thereof, and a doubled tying-string laced through said string-holes and its two end portions brought together and secured at one end portion of the tag to permanently fix the string 70 doubled relatively thereto and provide two tying-string ends at one end of the tag, substantially as described.

In testimony whereof I have hereunto set my hand in presence of two subscribing witnesses. 75

GEORGE W. MCGILL.
